(57) **CLAIM**

The ornamental design for the lid for beverage container, as shown and described.

DESCRIPTION

FIG. 1 is a front perspective view of the lid for beverage container with the cap in the closed position and the carabiner handle closed and in a first position;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a front perspective view of the lid for beverage container with the cap in the open position and the carabiner handle closed and in the first position;

FIG. 9 is a front view thereof;

FIG. 10 is a rear view thereof;

FIG. 11 is left side view thereof;

FIG. 12 is a right side view thereof;

FIG. 13 is a top view thereof;

FIG. 14 is a bottom view thereof;

FIG. 15 is a rear perspective view of the lid for beverage container with the cap in the closed position and the carabiner handle closed and in a second position;

FIG. 16 is a rear view thereof;

FIG. 17 is a left side view thereof;

FIG. 18 is a rear view of the lid for beverage container with the cap in the closed position and the carabiner handle closed and in a third position;

FIG. 19 is a left side view thereof;

FIG. 20 is a rear perspective view of the lid for beverage container with the cap in the closed position and the carabiner handle open and in the first position;

FIG. 21 is a rear view thereof; and,

FIG. 22 is a bottom perspective view thereof.

The broken lines depict portions of the lid for beverage container that form no part of the claimed design.

1 Claim, 22 Drawing Sheets
